United States Patent Office

Des. 189,625
Patented Jan. 17, 1961

189,625

COMBINED FORK AND SPOON

John I. McClelland, 3240 Lake Shore Drive, Chicago, Ill.

Filed Aug. 11, 1960, Ser. No. 61,697

Term of patent 14 years

(Cl. D44—29)

I claim:

The ornamental design for a combined fork and spoon, substantially as shown.
